ABSTRACT OF THE DISCLOSURE

An interlock is provided between a paper advance roller on a print module, which print module is slideable into a chassis of a larger unit, such as a reader-printer, and a conveyor within the chassis for conveying a finished print from the print module to an exit slot. The interlock comprises a pair of similar rotatable couplers which have extending lugs that are engageable with each other when the print module is in position within the chassis. One of the couplers is spring-biased on its rotational axis to provide relative movement if the lugs engage each other head-on during movement of the print module into the chassis. The conveyor provides a path from the paper advance device to the exit slot and includes a fixed plate through which drive rollers extend and a removable plate parallel thereto through which pressure rollers extend which are spring-biased against the drive rollers.

BACKGROUND OF THE INVENTION

Field of the invention

This invention relates to an interlock between a print module and a conveyor and more particularly to an interlock whereby a conveyor is driven by paper advance device in a print module.

Description of the prior art

In the prior art various types of interlocks are provided for interconnecting two rotatable members. For example, U.S. Pat. No. 2,056,305 to Thomas provides an interlock between a rotatable knob on a door and a mechanism behind the door so that the mechanism can be controlled by the knob when the door is closed. Furthermore, U.S. Pat. No. 2,475,573 to Smith et al. discloses a magnetic coupling between a sensing mechanism and a recording needle whereas U.S. Pat. No. 3,362,143 to Gullickson discloses an interlock for two shafts which are moved from an axially misaligned position to an axially aligned position. However, no means is shown in the above prior art for interconnecting two normally axially aligned devices and particularly for interconnecting a paper advance device and a print module with a conveyor for conveying a finished print from the print module to the outside of the larger chassis.

SUMMARY OF THE INVENTION

In accordance with this invention, a printer chassis having a print module movable into and out of the chassis is provided with means for interconnecting a paper advance means or device on the print module with a conveyor in the chassis for conveying a finished print from the printer to an exit slot in the chassis. This interconnecting means can include a first rotatably mounted coupler on the paper advance means and a second rotatably mounted coupler on the conveyor which couplers each have extending lugs that are engageable with the lugs on the other coupler for driving the conveyor from the paper advance means. Conveniently, one of the couplers may be spring-biased along its rotational axis toward the other coupler so that if the lugs come into engagement head-on when the print module is positioned

2

in the printer chassis, the spring-biased coupler will be displaced until energization of the print advance means causes relative rotary movement between the couplers. The conveyor provides a pathway for a print to be transported from the paper advance means of the print module to an exit slot in the chassis and includes a fixed plate

5 and a removable plate mounted generally parallel to the fixed plate. Spaced drive rollers on the conveyor are mounted so that they extend through the fixed plate and are engageable by spring-biased pressure rollers extending through a removable plate. The removable plate is made so that it can be taken out of the chassis in the event of a paper jam so that the jammed paper may be removed from the conveyor.

10 15 Additional features of the invention will become apparent from the description which follows, taken in conjunction with the accompanying drawings.

BRIEF DESCRIPTION OF THE DRAWINGS

20 FIG. 1 is a perspective view of a printer chassis having a slideable drawer containing a print module;

FIG. 2 is an enlarged fragmentary vertical section through the printer chassis of FIG. 1, showing the interrelationship between the conveyor and the print module;

25 FIG. 3 is a fragmentary top-plan view of the conveyor of FIG. 2 showing details of the interlock mechanism between the print module and the conveyor;

FIG. 4 is a fragmentary perspective view showing a means of attaching the removable plate portion of the 30 conveyor to the chassis;

FIG. 5 is a fragmentary view of the interlock means for coupling the print module to the conveyor; and

FIG. 6 is a horizontal section taken along line 6—6 of FIG. 3 showing the drive mechanism for the conveyor.

DESCRIPTION OF THE PREFERRED EMBODIMENT

In accordance with this invention, a printer chassis P, which may be part of a reader-printer may have a drawer 40 2 which is slideable into and out of the chassis and contains a print module M. The reader-printer is illustrated as having means for projecting an image of an original, such as microfilm 4, to a viewing screen 6 or for projecting an image to print module M where the hard copies thereof are made. The print module can use any copying technique known in the art such as a silver process or an electrostatic copying process.

Print module M includes a pair of spaced sidewalls 8 and 10 between which a supply roll 12 is journaled for dispensing receiving paper to be cut into sheets on which an image from an original document is reproduced. The finished prints, such as print 14, are fed through a paper advance means, such as a pair of drive rollers 16 mounted on drive shaft 18, as best seen in FIG. 3. Drive shaft 18 50 55 is driven through a belt 20 connected to a suitable power source, not shown. Conveniently, a pair of pressure rollers 22 are mounted for rotation about a short shaft 24 which is journaled in a leaf spring support 26 that biases rollers 22 against drive rollers 16 for feeding a finished print therebetween. Print 14 is directed by spaced guides 28 and 30, as shown in FIG. 2, into a passageway in conveyor C formed by fixed plate 32 and removable plate 34 parallel to plate 32.

Advantageously, a plurality of drive rollers 36, 38, and 60 65 70 75 80 85 90 95 98 100 105 110 115 120 125 130 135 140 145 150 155 160 165 170 175 180 185 190 195 200 205 210 215 220 225 230 235 240 conveyor C, a pair of spaced brackets 64, which may be attached to chassis P, as by welding, as shown in FIG. 2. As more clearly seen in FIG. 4, each bracket 64 may be provided with an elongated slot 66 which is adapted to receive an ear 68 of plate 34.

Spaced plates 32 and 34 form at their upper ends an exit slot 70 through which a print is fed which is deflected by a cover 72 which may be attached to the chassis as by hinge 74. If a paper jam should occur, cover 72 may be pivoted about hinge 74 in a clockwise direction, as viewed in FIG. 2 so that plate 34 can be pulled upwardly so that it is disengaged from slot 66 of bracket 64 and is removed. Once the jammed paper has been removed the plate may be reinserted into position as shown so that the pressure rollers engage the drive rollers.

As best seen in FIGS. 2 and 6, drive rollers are driven through an endless member, such as endless chain 76 which extends around cogs or gears 78, 80 and 82 on shafts 42, 44, and 46, respectively. In addition, the chain extends around an idler cog or gear 84 and around a drive cog or gear 86 on a stub shaft 88. It is through this gear 86 that the conveyor is driven. Constant tension is maintained on chain 76 by means of an idler gear 90 which is rotatably attached to one end of a link 92 pivoted at its other end to a bracket 94 on printer chassis P. Link 92 tends to be pivoted in a counterclockwise direction as viewed in FIG. 6, by coil spring 96 connected between arm 92 and bracket 94, as shown.

As stated above, conveyor C is driven through gear 86 which acts as a coupler and is normally biased by a coil spring 98 against a snap ring 100. Gear 86 is provided with a pair of spaced studs or lugs 102 extending outwardly therefrom which interlock with corresponding lugs 104 on coupler 106 which is fixedly attached to drive shaft 18 and rotatable therewith, as best seen in FIG. 3.

Thus, it can be seen that when drawer 2 is slid into chassis P, as from the left as viewed in FIG. 3, lugs 104 on coupler 106 will normally move between lugs 102 on coupler or gear 86 so that upon energization of the paper feed means through shaft 18, the conveyor will be driven through the coupling to advance a finished print 14 from print module M through conveyor C to the exit slot. Of course, if lugs 102 are aligned with lugs 104 so that they meet head-on when the drawer is closed, coil spring 98 will permit gear 86 to be displaced to the right, as viewed in FIG. 3. However, when shaft 18 begins to rotate, the rounded ends of the lugs will cause lugs 104 to slide off the ends of lugs 102 so that spring 98 can move gear coupler 86 to the left so that the lugs are interengaged to drive the conveyor. When it is necessary to service the print module, drawer 2 can be withdrawn and the lugs will become uncoupled.

From the foregoing, the advantages of this invention are readily apparent. A coupling device has been provided between a print module and a conveyor within a printer chassis which provides a rapid and easy coupling and uncoupling of the two units so that the conveyor may be driven from the same power source which drives the paper feed means. In addition, a conveyor is provided which has a removable panel for eliminating any paper jams, should they develop.

The invention has been described in detail with particular reference to a preferred embodiment thereof, but it will be understood that variations and modifications can be effected within the spirit and scope of the invention.

I claim:

1. An improved printer comprising:
  - (a) a printer chassis including a housing and having means defining a print exit slot in said housing;
  - (b) a print module having a print-making path and being supported on said chassis for movement into and out of said housing;
  - (c) means on said print module for receiving a supply of print paper;

(d) activatable print paper advance means, mounted on said print module, for moving received print paper along said print-making path;

(e) a print paper conveyor mounted on said chassis within said housing and including means for conveying a finished print from said print module to said print exit slot; and

(f) interlock means for drivingly coupling said print paper advance means of said print module and said print paper conveyor in response to movement of said print module into said printer chassis.

2. The invention defined in claim 1 wherein said interlock means includes:

a first rotatable coupler drivable by said paper advance means;

a second rotatable coupler on said conveyor for driving said conveyor; and

first and second lug means on said first and second couplers, respectively, engageable when said print module is on said chassis for driving said conveyor.

3. The invention defined in claim 2 wherein one of said couplers is resiliently biased toward the other of said couplers.

4. The invention defined in claim 1 wherein said print paper conveyor includes:

means defining a pathway for conveying a finished print from said print module to said slot defining means;

a plurality of spaced drive rollers along said pathway coupled to said interlock means; and

pressure rollers positioned along said pathway adjacent said drive rollers for urging said finished prints against said drive rollers so that said finished prints are conveyed along said pathway to said exit slot defining means.

5. The invention defined in claim 4 wherein said pathway defining means includes:

a fixed plate extending from adjacent said paper advance means to said exit slot defining means, said drive rollers extending therethrough to said pathway; and

a removable plate parallel to but spaced from said fixed plate, said pressure rollers being attached thereto and being spring-biased toward said drive rollers.

6. In combination, a printer module having print paper advancing means mounted thereon; a printer chassis supporting said printer module for movement into and out of said chassis and having a print conveyor mounted therein; and an interlock for interconnecting said print paper advancing means and said print conveyor, said interlock including:

a first coupler rotatably mounted on said printer module and having at least one lug extending therefrom, said first coupler being connected to said paper advancing means for rotation thereby; and

a second coupler rotatably mounted on said conveyor and having at least one lug extending toward said lug of said first coupler, said lugs being engageable upon movement of said print module into said printer chassis;

at least one of said couplers being mounted for movement in directions toward and away from the other of said couplers and including spring bias means for urging said one coupler in the direction toward the other of said couplers.

7. The invention defined in claim 6 wherein said conveyor has a drive chain and one of said couplers includes a gear engageable with said chain to drive said conveyor.

8. Improved copying apparatus of the type having an operative path along which copy material is moved during a copying cycle, said apparatus comprising:

(a) a main chassis having walls therearound, said walls having a copying module opening and a copy material egress opening formed therein;

- (b) a copying module supported on said main chassis for movement between an operative position substantially within said main chassis and a servicing position withdrawn from said main chassis, said copying module including closure means cooperable with the walls of said main chassis in said operative position for rendering said apparatus interior substantially light-tight;
- (c) means on said module for receiving a supply of copy material;
- (d) first feed means on said copying module for moving copy material along the operative path of said apparatus;
- (e) second feed means on said main chassis for feeding copy material to said egress opening;
- (f) drive means coupled to one of said first and second feed means;
- (g) interlock means for connecting said drive means to the other said first and second feed means upon movement of said module to said operative position and for allowing disconnection of said drive means from said other of said first and second feed means by movement of said copying module toward said servicing position.
9. The invention defined in claim 1 further including

5

first guide means on said module for guiding received copy material along the copy making path of said apparatus and second guide means on said main chassis for guiding copy material to said egress opening, said first and second guide means being located so as to cooperatively form a copy material guide path from said copying module to said egress opening when said module is in said operative position.
